UNITED STATES PATENT OFFICE.

ANDREW CULLEN, OF MASSILLON, OHIO.

GUIDE-BOX FOR ROLLING-MILLS.

1,398,843.

Specification of Letters Patent.

Patented Nov. 29, 1921.

Application filed October 30, 1919. Serial No. 334,545.

To all whom it may concern:

Be it known that I, ANDREW CULLEN, a citizen of the United States, residing at Massillon, in the county of Stark and State of Ohio, have invented a new and useful Guide-Box for Rolling-Mills, of which the following is a specification.

This invention has reference to guide boxes for rolling mills, and its object is to 10 provide a guide box, for use in producing bars from ingots, which shall be free from certain objectionable features found in other guide boxes.

In rolling mills, especially those for producing bars of round cross-section, the last passing of the bar between the rolls requires the use of a guide of elliptical cross-section, while the pass in the rolls is of round cross-section, and the guide is so positioned that 20 during the final reduction in the bar, the latter is held in a manner to avoid distortion or undue strain.

The invention includes a guide box usually located in front of the last pass of the rolls, 25 although, of course, it may be utilized at other points and for other purposes. Within the box are guide holders and guides, each being two-part structures associated for co-action. The guide holders are held in suitable position by set screws, to permit adjustment and change, and one of them is so arranged as to be held in position after adjustment, while the other is also adjustable toward and from the first guide holder at will. 30 Each guide holder is arranged to receive an appropriate one of the guides, which latter are suitably shaped blocks each constituting one half of the completed guide. One of the guide holders is so arranged that it may 35 be easily moved laterally from or toward the other guide holder, to permit initial centering and subsequent firm holding of the guide while the rolling is proceeding. Provision is made for the quick movement of the guide 40 holder with the guide fast therein to open the guide sufficiently for the introduction of the bar, and to subsequently close the guide to closely embrace the bar, while the latter is being pulled by the rolls through the pass 45 to cause the final shaping of the bar into cylindrical form.

Provision is made for the attachment of the invention to existing rolling mills without necessitating structural changes, so that the advantageous features of the invention 55 may be utilized without such expense as would be necessary to install new parts as replacements of existing parts in installed rolling mills.

The invention will be best understood 60 from a consideration of the following detailed description, taken in connection with the accompanying drawings forming part of this specification, with the understanding, however, that the invention is not confined 65 to any strict conformity with the showing of the drawings, but may be changed and modified, so long as such changes and modifications mark no material departure from the salient features of the invention as expressed in the appended claims.

In the drawings.

Figure 1 is a side elevation of a rolling mill equipped with the invention.

Fig. 2 is a front elevation thereof.

Fig. 3 is a horizontal section in a plane corresponding to the meeting faces of the rolls.

Fig. 4 is a section on the line 4—4, Fig. 2, but drawn on a larger scale.

Fig. 5 is a view similar to Fig. 4, but taken in a front-to-rear plane between the guides.

Fig. 6 is a section on the line 6—6 of Fig. 4.

Fig. 7 is a section on the line 7—7 of Fig. 6.

Fig. 8 is a perspective view of a portion of one of the guides.

Referring to the drawings, there is shown 90 a rolling mill stand A, in which are mounted suitable rolls 1 and 2, provided with passes 3, such parts requiring no particular description, since they may be such as are common to rolling mills and especially those 95 adapted for the production of round rods or bars.

The invention is concerned particularly with a guide box, and parts connected therewith, for use especially with the last pass 3 where 100 the bar is reduced to a round cross-section or cylindrical form.

The guide box comprises a hollow frame 4 of considerable front-to-rear extent, and includes a top member 5, side members 6 and 7, respectively, and a bottom member 8. The 5 side members 6 and 7, each has a projecting portion 9 terminating in a nose 10 so that the projecting portion 9 may enter into close relation to the rolls, whereby the bar, being rolled, may be supported very close to the 10 rolls when gripping said bar to draw it through the pass, to which the bar is presented. The bottom member 8 is extended from the side members 6 and 7 away from the nose portions 10 of the side members, and 15 the under surface of the bottom member 8 is provided with a rib 11 seated in a groove 12 formed in the upper surface of a supporting or rest bar 13 carried by and extending between uprights or columns 14 forming part 20 of the roll-carrying stand. The bar 13 is designed to sustain the guide box in position along the rolls, and clamp screws 15 extending through a longitudinal slot 16 in the supporting bar 13 are tapped into the rib 11 25 and bottom plate 8 to hold the guide box firmly in desired positions.

The top 5 is formed with a slot 17 extending crosswise of the guide box, which slot has an intermediate expansion 18 and a continuation 19 opening into the interior of 30 the guide box. The purpose of the slot 17, with its expansion 18 and continuation 19, is to pass set screws 20, 21, 22, one of the set screws carrying a nut 23 lodged in and movable along the expanded portion 18 of the slot 17.

Within the guide box are located two substantially channel-shaped members 24, 25, together constituting a guide holder, with 40 the two members movable toward and from each other, and each comprising a side plate 26 and end plates 27, 28 with the inner faces of the end plates beveled as indicated at 29. The guide holder member 25 is clamped in 45 the guide 4 by means of the set screw 20, and its position with relation to the side 6 of the guide box is determined by back set screws 30 carried by the side wall 6 of the guide box.

50 The guide holder member 24 is provided with an internal screw-threaded neck 31, and the side member 7 has a passage 32 therethrough for the neck.

Within the guide holder there is located 55 a guide formed of two like blocks 33, each with an interior groove 34. The set screws 21 and 22 extend through the end walls 27 of the respective guide holder members 24 and 25, and engage and lock the guide blocks 60 in the respective holder members, but the guides are adjustable toward and from each other, except that the guide holder 25 may be locked against movement in the guide box 4 by the set screw 20.

When the guide box 4 is secured to the bar 13, there is still provision for the lateral adjustment of the guide by suitable means such as a screw rod 34^a having a threaded end 35 entering the screw socket 31, the guide holder member 24 having a limited 70 range of adjustment in the guide box 4, even though the guide holder 25 be locked against movement by the set screw 20.

There is also provision made for the up and down adjustment of the guide blocks 33, 75 which blocks each have beveled or wedge-shaped lugs 36 to engage the beveled faces 29 of the plates 27, 28. Each guide block 33 is formed at one end with a lug 37 to limit the movement into the guide holder 80 toward the throat of the rolls, while that end of each guide block toward the throat of the rolls is prolonged and narrowed similarly to the side plates 6 and 7 of the guide box. In order to permit up and down adjustment of the guide blocks, enough play is provided between these blocks and the end portions 27, 28 of the guide holder members 85 to admit shims or liners 38, so that by the introduction of shims, or the removal of 90 shims and the proper adjustment of the set screws 21 and 22, the longitudinal center line of the guide blocks may be raised and lowered so as to properly conform with or match the longitudinal center line of that pass in 95 the rolls opposite which the guide box is located. These shims adjust the guides for wear.

In order to provide for a rapid opening and closing of the guides, various devices 100 may be used as, for instance, right and left hand screws or multiple-thread screws of long pitch, or other suitable means. In the drawings, such adjustment is accomplished by the screw 34^a having the threaded end 35 105 already referred to, while the other end has a screw threaded extension 39 of opposite pitch to the threaded end 35. Fast to the neighboring column 14 of the stand A is a plate 40 held in place by bolts or screws 41 110 and passes the end 39 of the screw 34^a, which, at its outer terminal portion, is squared as shown at 42, or otherwise suitably shaped to receive the hub end 43 of a crank or handle 44, whereby the screw may be turned about its longitudinal axis at will. The plate 40 is provided with lugs or projections 45, to which is bolted a strap 46 having a series of perforations 47 therein in any one of which may be lodged a stop pin 48 extending into 120 the path of the handle 44 to limit the movement of the handle and thus regulate the stroke thereof.

The end 39 of the screw carries a nut 49 seated in a recess in a locking box 50 having a passage 51 through which the screw rod 34^a extends. The box 50 is held to the plate 40 by means of bolts 52 or in any other appro-

priate manner, while the nut 49 is prevented from turning with the screw rod 34^a by the locking box 50.

Before the bar being rolled is entered into the pass of the rolls where it is completed, the handle 44 is moved in the proper direction, which may be assumed to be upwardly away from the stop 48 to thereby cause the end 35 of the screw rod 34^a to screw into the 5 socket 31 and screw outwardly through the nut 49. The result of this is that the guide block holder 24 and the guide block therein are moved positively away from the other guide block holder 25 and guide block there- 10 in, the latter holder being at the time clamped fast to the guide box by the set screw 20. The extent of separation of the guide blocks is determined by other back set screws 53 carried by the side plate 7 of the 15 guide box.

Guide mountings, as heretofore provided, have been more or less complicated in construction and awkward in operation and have required the stopping of the machine 20 and caused considerable delay when adjustments have been needed.

In accordance with the invention, adjustments may be accomplished while the machine is in operation and without causing 25 any delay. It is of importance that the guides may be opened and closed in a positive manner, instead of the customary arrangement where the guides are permanently placed in the box, making it difficult 30 to get a bar that is a little over size through the guides, or where the bar being rolled is utilized to push the guide away, such a procedure often causing a great deal of delay in getting the bar into the rolls.

With the invention, the guides are positively spread to an extent permitting the movement of the bar by the operator into a pass to be properly gripped by the rolls, whereupon the guides are brought into holding 40 relation to the bar without material exertion, which latter oftentimes mars the bar permanently.

It may sometimes be desirable to operate the guide blocks without the rapid opening 45 and closing means, and in such event, the rod 34^a may be readily unscrewed from the socket 31, whereupon the guide blocks may be operated in the ordinary manner.

What is claimed is:—

1. A guide box structure for rolling mills comprising a frame, a pair of guide holders each substantially channel shaped and located within the frame, individual guide blocks adjustable within each guide holder, set screws passing through the guide holders and holding the guide blocks in the holders, and other set screws for retaining one of the guide holders in fixed position.

2. A guide box structure for rolling mills

comprising a frame, a pair of guide holders 65 within the frame, individual guide blocks within each guide holder, means provided on the guide holders for holding the guide blocks therein, means for adjusting one of the guide holders into positions spaced from 70 one side of the frame, and means for retaining the same guide holder in adjusted positions.

3. A guide box structure for rolling mills, comprising a hollow frame, a pair of guide 75 holders within the frame and each consisting of a channel shaped part with the inner faces of the end members beveled, individual guide blocks within each guide holder, shims or liners interposed between the beveled in- 80 ner faces of the lower end members of the guide holders and the lower faces of the guide blocks, and means provided on the end members of the guide holders opposite the shims or liners and engaging the guide 85 blocks to hold the same in place.

4. A guide box structure for rolling mills comprising a hollow frame, a pair of guide holders located within the frame and each consisting of side plates and top and bottom 90 end plates, the inner faces of the end plates being beveled, individual guide blocks within each guide holder, each block having wedge shaped lugs to engage the beveled inner faces of the said end plates, and means 95 for holding the blocks within said holders.

5. A guide box structure for rolling mills comprising a hollow frame, a pair of guide holders located within the frame and each consisting of side plates and top and bottom 100 end plates, the inner faces of the end plates being beveled, individual guide blocks within each guide holder, shims or liners interposed between the inner faces of the bottom end plates and the lower faces of the guide 105 blocks, each block having wedge-shaped lugs engaging said shims, and means for securing the blocks within said holders.

6. A guide box for rolling mills, comprising a frame adapted to be positioned in front 110 of the rolls, fixed and movable guides carried by the frame, a manipulating handle, a right and left hand screw carried by the handle and connected with the movable guide to positively move the same toward and from 115 the fixed guide, and means for limiting the movement of the handle.

7. A guide box for rolling mills, comprising a frame adapted to be positioned in front 120 of the rolls, fixed and movable guides carried by the frame, a manipulating handle, means carried by the handle and connected with the movable guide to positively move said guide toward and from the fixed guide, a plate over which the handle is moved, said plate 125 being provided with a series of holes, and a stop pin inserted in one of said holes to limit the movement of the handle.

8. A guide box for rolling mills comprising a frame adapted to be positioned in front of the rolls, fixed and movable guides carried by the frame, a manipulating handle, a right and left hand screw carried by the handle and connected with the movable guide to positively move the same toward and from the fixed guide, a plate over which the handle is moved, said plate being provided with a series of holes, and a stop pin inserted in one of said holes to limit the stroke of the handle.

9. A guide box structure for rolling mills comprising a frame adapted to be fixed to the rolling mill opposite a chosen one of the passes of the rolls, a divided holder in the frame, a divided guide mounted in the holder, means for securing the guide holder in the frame, means for securing the guide in the guide holder, and positively acting means for spreading and contracting the guide to admit and embrace the work.

10. A guide box for rolling mills comprising a frame adapted to be positioned in front of a pass of the rolls of the mills, a two-part guide holder with means for securing one part of the holder in the frame with the other part of the holder movable in the frame toward and from the first-named part of the holder, a two-part guide for the work, means for securing each part of the guide in a respective part of the guide holder, and means under the control of an operator for positively moving one part of the guide holder, with the part of the guide fast therein, from and toward the other part of the guide, to provide free passage through the guide of the work and the subsequent embracing of the work.

11. A guide box structure for rolling mills comprising a frame adapted to be fixed to the rolling mill opposite a chosen one of the passes of the rolls, a divided holder in the frame, a set screw carried by the frame for locking one of the holders, other set screws carried by the holders, guide blocks together forming a divided guide held individually by the set screws of the holders, and positively acting means for moving one of the guide holders and the guide block therein in both directions relative to the other holder and guide.

12. A guide box structure for rolling mills comprising a frame adapted to be fixed to the rolling mill opposite a chosen one of the passes of the rolls, a divided holder in the frame, back set screws for the divided holder members carried by the frame, a set screw carried by the frame for locking one of the holders, set screws carried by the holders, guide blocks together forming a divided guide held individually by the set screws in the holders, and positively acting means for moving one of the guide holders and the guide block therein in both direc-

tions with relation to the other holder and guide therein.

13. A guide box structure for rolling mills comprising a frame adapted to be fixed to the rolling mill opposite a chosen one of the passes of the rolls, a divided guide holder mounted in the frame, a divided guide mounted in the corresponding parts of the holder, means interposed between the guide portions and the respective holder portions for taking up wear in the guide, each of said guide holders having limited movement within the frame, means for clamping one of the holders within the frame so that it becomes a fixed holder, means for effecting adjustment of the position of this relatively fixed holder prior to the clamping thereof, means for securing the individual parts of each guide to the corresponding holder portion whereby each guide portion and holder portion are fixed relatively, means for effecting a relatively slow adjustment of the position of the movable guide holder portion toward the fixed guide holder portion, and means for effecting a rapid movement of the movable holder portion either toward or away from the fixed holder portion.

14. A guide box structure for rolling mills comprising a frame adapted to be fixed to the rolling mill opposite a chosen one of the passes of the rolls, a guide and holder therefor mounted in the frame, said guide and holder being divided to permit the guide members to be spread apart or approach, means for causing the positive movement of the guide members toward and from each other, comprising a right and left screw with one end in engagement with one member of the guide holder, a nut for the other end of the screw, means for holding the nut to the frame of the rolling mill, and a handle for the screw, whereby the latter may be rocked to positively separate or approach the members of the guide.

15. A guide box structure for rolling mills comprising a frame adapted to be fixed to the rolling mill opposite a chosen one of the passes of the rolls, a divided guide and divided holder therefor mounted in the frame, means for fixing one holder in the frame, a right and left hand screw connected at one end to the other holder, a nut connected to the frame of the mill and traversed by one end of the screw, a manipulating handle for the screw, a stop pin in the path of the handle, and a carrier therefor with a plurality of receptacles for the stop pin to permit movements of the handle and corresponding movements of the screw and guide member connected thereto in accordance with the position of the stop.

16. A guide box structure for rolling mills comprising a hollow frame, a pair of guide holders each consisting of a substantially channel shaped member located within the

hollow frame, individual guide blocks within each guide holder, means provided on the guide holders for holding the guide blocks therein, means for adjusting one of the 5 guide holders in positions spaced from one side of the frame, means for retaining the same guide holder in adjusted positions, and means connected with the other guide holder for rapid adjustment of its position

within the frame toward or from the fixed 10 guide holder.

In testimony that I claim the foregoing as my own, I have hereto affixed my signature in the presence of two witnesses.
